UNITED STATES PATENT OFFICE

MARTIN L. HUNKER, OF DOVER, OHIO, ASSIGNOR TO THE REEVES MANUFACTURING COMPANY, OF DOVER, OHIO, A CORPORATION OF OHIO

BOTTOM CONSTRUCTION FOR CANS

Application filed December 6, 1927. Serial No. 238,070.

The invention relates to sheet metal cans such as ash cans and the like, and more particularly to a reinforced construction of such cans, and is an improvement upon the construction disclosed in the application of V. P. Wendle, Serial No. 203,156, filed July 2, 1927, and an application of R. J. Curtis Serial No. 232,323, filed November 10, 1927.

As stated in the prior applications, above referred to, it has been common practice to rivet a rolled iron hoop around the lower end of this type of can for the purpose of taking the wear to which such cans are subjected by being dragged across cement floors, and the like, when filled with ashes or other heavy material.

It has also been customary to rivet a similar rolled iron hoop around the open upper end of such cans to reinforce the same at this point.

The prior applications, above referred to, provided for attaching a rolled iron hoop at the bottom of the can, without the use of rivets, thus reducing the labor and manufacturing cost of such cans.

The object of the present improvement is to simplify and improve such constructions; to make the reinforced structure stronger and more durable; and to provide a reinforced can which is adapted for nesting for shipping purposes and the like.

The above and other objects may be attained by constructing the can in the manner illustrated in the accompanying drawing, in which—

Figure 1 is a longitudinal, sectional view through the upper and lower portions of the improved can, with the reinforcing hoops inserted therein, prior to the final operation which attaches the hoops to the can;

Fig. 2, a similar view of the finished can, with the hoops attached therein; and

Fig. 3, a section taken substantially on the line 3—3, Fig. 2.

Similar numerals refer to similar parts throughout the drawings.

The improved can may be slightly tapered, in order that a plurality of the cans may be nested together for shipping or storage purposes.

The can is preferably corrugated longitudinally, throughout the greater portion of its body, as illustrated at 5, the corrugations terminating at the upper and lower end portions in the outturned substantially horizontal peripheral flanges 6 and 7, respectively.

The body portion of the can, as initially formed, is provided with the upturned peripheral flange 8, extending upward from the periphery of the upper flange 6, and with the downturned, peripheral flange 9, extending downward from the periphery of the lower flange 7, the flange 9 terminating in the outturned peripheral flange 10.

The bottom 11, of the can, is stamped from a sheet of metal and is initially formed with the peripheral, upturned flange 12, having the outturned peripheral flange 13, and depending peripheral flange 14, forming an upwardly disposed, inverted channel portion terminating in the outturned peripheral flange 15, preferably located considerably below the plane of the bottom 11.

The flange 14 is of suitable height and circumference to fit snugly within the flange 9 of the body, the flange 13, of the bottom, contacting with the under side of the flange 7, of the body, while the flange 15, of the bottom, contacts with the under side of the flange 10, of the body, in the manner illustrated in Fig. 1, when the bottom is inserted into the lower end portion of the body.

The rolled iron hoop 16 is provided in its periphery with the inclined groove 17, extending downward and inward from the top of the hoop and terminating at the substantially horizontal shoulder 18, spaced from the lower edge of the hoop.

In assembling the hoop 16, and bottom, upon the body of the can, the bottom is inserted into the lower end of the can, as above described, and the hoop is inserted into the bottom, as shown in Fig. 1, the upper edge of the hoop being located between the flanges 12 and 14, and contacting with the under side of the flange 13.

By the use of a seaming roller, or the like, the flanges 10 and 15, of the body and bottom respectively, are formed into a double seam

19, and the flanges 9 and 14, of the body and bottom respectively, are pressed tightly into the inclined groove 17 of the hoop, as shown in Fig. 2.

5 The entire joint, between the body and bottom of the can, is thus received in the inclined, peripheral groove of the hoop, presenting no exterior obstruction, and permitting the can to be easily inserted within a similar can, 10 thus providing for nesting of the cans for shipping or storing the same.

It will be obvious, from an inspection of Fig. 2, that the flanges 9 and 14, when pressed into the inclined groove of the hoop, are tapered at a greater angle than the body portion 15 of the can, thus securely locking the hoop in position at the lower end of the can.

The upper hoop is adapted to be received within the upstanding flange 8, at the upper 20 end of the can, and to rest upon the flange 6 thereof. The internal groove or reduced portion 21 is formed at the upper end portion of this hoop.

With the hoop 20 in place, as shown in Fig. 25 1, the free, upper portion of the flange 8 is then pressed or formed over the upper edge of the hoop, and down upon the inner side thereof, seating in the groove 21 of the hoop, as shown in Fig. 2.

30 The rolled hoops are thus attached to the upper and lower ends of the can without the expense and labor of riveting the same, and it will be seen that these hoops are firmly and rigidly held in place, with the lower 35 hoop extending below the bottom of the can, so that only the hoop contacts with the floor or ground, whereby all of the wear caused by sliding upon the floor is received by the hoop, preventing rapid wear of the bottom 40 of the can.

The hoops are not only firmly and rigidly held in place, but the construction is such that the cans may be easily nested together, and the hoops may be easily and quickly assembled upon the can, in a simple operation.

I claim:

1. A sheet metal can comprising a body portion having an outturned, substantially horizontal, annular flange at its lower portion, terminating in a downturned peripheral flange, a bottom having a peripheral, upwardly disposed, inverted channel portion adapted to be received within the lower end portion of the body and to contact with said outturned flange, the inner side of the annular channel portion of the bottom being flush with the inner wall of the body, and a hoop located within the annular channel portion of the bottom and having a tapered 50 peripheral groove into which the lower end portion of the body and the termination of the channel portion are adapted to be pressed.

2. A sheet metal can comprising a body portion having an outturned, substantially horizontal, annular flange at its lower por-

tion, terminating in a downturned peripheral flange, a bottom having a peripheral, upwardly disposed, inverted right angular channel portion adapted to be received within the lower end portion of the body and to contact with said outturned flange, the inner side of the annular channel portion of the bottom being flush with the inner wall of the body, and a hoop having a right angular upper portion located within the annular channel portion of the bottom and having a tapered peripheral groove into which the lower end portion of the body and the termination of the channel portion are adapted to be pressed.

70 In testimony that I claim the above, I have 80 hereunto subscribed my name.

MARTIN L. HUNKER.
